DESIGN FOR A LADY'S BELT

Kenneth M. Smith, Albuquerque, N. Mex.

Application February 6, 1945, Serial No. 117,790

Term of patent 7 years

(Cl. D3—10)

To all whom it may concern:

Be it known, that Kenneth M. Smith, a citizen of the United States, residing at Albuquerque, in the county of Bernalillo and State of New Mexico, has invented a new, original, and ornamental Design for a Lady's Belt, of which the following is a specification, reference being had to the accompanying drawing, forming part thereof, wherein:

I claim:

The ornamental design for a lady's belt, as shown.

KENNETH M. SMITH.
